US0D1050091S

(12) **United States Design Patent** (10) Patent No.: **US D1,050,091 S**
(45) Date of Patent: ** Nov. 5, 2024

(54) **RADIO FREQUENCY IDENTIFICATION TAG**

(71) Applicant: **MEET CO., LTD.**, Tokyo (JP)

(72) Inventor: **Ken Kitamura**, Tokyo (JP)

(73) Assignee: **MEET CO., LTD.**, Tokyo (JP)

(**) Term: **15 Years**

(21) Appl. No.: **35/518,856**

(22) Filed: **Nov. 1, 2022**

(80) **Hague Agreement Data**

Int. Filing Date: **Nov. 1, 2022**

Int. Reg. No.: **DM/227069**

Int. Reg. Date: **Nov. 1, 2022**

Int. Reg. Pub. Date: **Nov. 3, 2023**

(30) **Foreign Application Priority Data**

May 2, 2022 (JP) ..... 2022-9500 D

(51) **LOC (14) Cl.** **14-03**

(52) **U.S. Cl.**

USPC **D14/230**

(58) **Field of Classification Search**

USPC D14/230, 231-240, 238.1, 243, 299, 358,
D14/217, 138; D13/182; D23/364, 366,
D23/367

CPC H01Q 1/243; H01Q 1/36; H01Q 1/50;
H01Q 7/00; H01Q 9/0407; H01Q 9/045;
H01Q 9/285; H04B 1/034; H04B
2001/0408; H05K 11/00

See application file for complete search history.

(74) Attorney, Agent, or Firm — Greenblum & Bernstein,
P.L.C.

(57) **CLAIM**

The ornamental design for a radio frequency identification tag as shown and described.

DESCRIPTION

- 1.1: Bottom
- 1.2: Back
- 1.3: Right
- 1.4: Left
- 1.5: Top
- 1.6: Front

1 Claim, 6 Drawing Sheets
